(57) **CLAIM**

The ornamental design for a belt strap adjuster, as shown and described.

DESCRIPTION

FIG. 1 is a front, top, and right perspective view of a belt strap adjuster, showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 shown in FIG. 2;

FIG. 9 is a front, top, and right perspective view thereof, showing a state in which a cap is half open; and,

FIG. 10 is a front, top, and right perspective view thereof, showing a state in which the cap is fully open.

The long dash short dash broken lines and arrows shown in FIG. 2 are used to identify the cross-sectional view and form no part of the claimed design. The evenly spaced broken lines shown in FIGS. 1-10 depict portions of the belt strap adjuster that form no part of the claimed design. The dash dot dash broken lines shown in FIG. 8 depict the boundaries of the claimed design and form no part of the claimed design.
